UNITED STATES PATENT OFFICE.

EDWARD L. McDIVITT, OF BELVIDERE, ILLINOIS.

PENCIL-SHARPENER.

SPECIFICATION forming part of Letters Patent No. 700,071, dated May 13, 1902.

Application filed December 2, 1901. Serial No. 84,493. (No model.)

To all whom it may concern:

Be it known that I, EDWARD L. McDIVITT, a citizen of the United States, residing at Belvidere, in the county of Boone and State of Illinois, have invented certain new and useful Improvements in Pencil-Sharpener, of which the following is a specification.

This invention relates to improvements in pencil-sharpener in which the pencil is held in place by a spring and the point of the pencil located in a recess and a stop to the point.

In the accompanying drawings, Figure 1 is a perspective view of my improved pencil-sharpener. Fig. 2 is a face view of the same. Fig. 3 is a rear view. Fig. 4 is a side elevation. Fig. 5 is a lengthwise central section. Fig. 6 is a transverse section on dotted line *a*, Fig. 2.

A plate 1, forming the main support for the pencil, is formed from sheet material and has its upper end 2 bent at an angle to the face and provided with an opening 3. The face has a lengthwise opening 4 and a smaller opening 5.

25 A bridge 6 is located at the lower end of the opening 4, being in semicircular form and having an opening 7. The edges 8 of this bridge are undercut and fit corresponding projections extending from the sides of the opening 4. The upper face of this bridge has a recess 9, conical in form.

A plate-spring 10 has an opening 11, the lower portion of the spring held in place between the bridge and front plate, as shown at Fig. 6. The upper portion of this plate-spring is curved away from the rear face of the plate 1, as shown at Fig. 4.

The lead-pencil is placed through the opening 3 in the end 2, under the spring 10, and in the conical recess. The knife 12 is drawn down the face of the plate 1, thereby severing a shaving from the pencil. The pencil is partially turned and another shaving removed, and so on until the lead enters and passes through the opening 7 and rests against the end of the lower opening 5, as shown in Fig.

45 5. The angle of the face of the plate 1 with respect to the lengthwise direction of the pencil is such as to give the sharpened end of the

pencil a graceful taper. The opening 7 in 50 the bridge is such as to hold the lead and prevent it moving out sidewise, thereby holding the lower portion of the plate in connection with the pencil. The conical recess 9 in the upper face of the bridge serves to guide the 55 lead of the pencil into the opening. The spring 10 presses the pencil against the plate 1 and prevents the sharpener becoming disengaged from the pencil. At Fig. 1 is shown the manner of holding the sharpener and pencil and the application of the knife.

I claim as my invention—

1. A pencil-sharpener comprising a sheet-metal plate provided with a lengthwise opening and a perforated end bent substantially 65 at right angles to the face of the plate and a bridge with a peripheral opening located across the opening in the plate.

2. A pencil-sharpener comprising a sheet-metal plate provided with a lengthwise opening, a bridge with a peripheral opening located across the opening in the plate leaving a portion of the lengthwise opening each side of the bridge, and a spring secured to the back of the plate.

3. A pencil-sharpener comprising a plate with a lengthwise opening and an end provided with an opening, a bridge located across the lengthwise opening and having a conical recess and a peripheral opening.

4. A pencil-sharpener comprising a sheet-metal plate provided with a lengthwise opening, a bridge with a peripheral opening located across the opening in the plate and a plate-spring secured to the back of the plate 85 and held in place by the bridge.

5. A pencil-sharpener comprising a sheet-metal plate provided with a lengthwise opening, a bridge with a peripheral opening located across the opening in the plate, and a 90 plate-spring with a lengthwise opening secured to the back of the plate and held in place by the bridge.

EDWARD L. McDIVITT.
